CLAIM

We claim the ornamental design for a radiocommunication equipment, as shown.

DESCRIPTION

FIG. 1 is a front view of the radiocommunication equipment showing our new design;

FIG. 2 is a back view of the radiocommunication equipment;

FIG. 3 is a top view of the radiocommunication equipment;

FIG. 4 is a bottom view of the radiocommunication equipment;

FIG. 5 is a right side view of the radiocommunication equipment;

FIG. 6 is a left side view of the radiocommunication equipment; and,

FIG. 7 is a perspective view of the radiocommunication equipment.

The broken line disclosure is for illustrative purposes only and forms no part of the claimed design.
